GOLF CLUB

William H. McKenna, Boulder, Colo.

Application November 25, 1933, Serial No. 699,755

14 Claims. (Cl. 273—77)

This invention relates to golf clubs and, more particularly, to a gauge for spacing the club from the ground at the beginning of a drive or when the exigencies of the game make it necessary or desirable to "tee up" the golf ball. The invention is particularly applicable to or useful when combined with one of the so-called "woods", such as the "driver", "brassie", or "spoon", which are commonly used to impart 10 the maximum distance possible to the flight of the golf ball.

When the ball is teed up at the beginning of the drive, either from the tee or from the course, the bottom of the ball is an appreciable distance 15 from the ground. To make the proper stroke, it is necessary that the forward path of the golf club be such that the bottom part or sole of the club be a predetermined height above the ground. It is thus desirable to space the golf 20 club from the ground at the beginning of the stroke.

One of the objects of the invention is to provide an attachment which can be applied to the head of the golf club without altering the balance or feel of the club and which, when in the operative position, will space the bottom of the club at a predetermined distance from the ground at the beginning of the stroke. In the event that the forward swing of the clubhead 30 approaches the ground closer than the gauge distance, the contact of the ground and the gauge will cause the gauge to be retracted immediately and with no effect on the path of the club.

By starting the back swing with the clubhead 35 above the ground, the known tendency of some golfers to dig the club head into the ground on the forward stroke is greatly lessened and in most cases entirely obviated by the use of this device.

The nature of the invention is such that the gauge when not in the operative position, is retracted so that it lies flat with the sole of the club and forms a part thereof. It is thus possible by setting the gauge in a non-operative 45 position to use the club precisely as if the gauge were not a part thereof. This is of value when the ball has such a lie that the shot is a proper one for a brassie or a spoon.

The invention may be readily understood by reference to the accompanying drawing, in which—

Figure 1 is a plan view of the bottom of the club to which the invention is attached;

Figure 2 is a cross-section on line II—II of Figure 1;

Figure 3 shows a right handed club at the beginning of the stroke with a gauge in operative position; and

Figure 4 is a detail perspective view showing a gauge and part of the means for fastening it to the sole of the club.

As illustrated in the drawing, the gauge consists of a plate 2 of generally rectangular shape, one end of the plate 3 being enlarged and shaped like a cam. Through the enlarged portion 3 is an opening 4 through which is fitted a hinge pin 5. In order to fasten the gauge to the bottom 6 of the golf club 7, two members 8, (only one of which is shown in Figure 4) are provided. The member 8 has an enlarged end 9 through which an opening 10 is drilled to accommodate pin 5. The member 8 is fastened to club 7 by means of screws 11 which pass through the hole 12 provided in member 8. In order that the gauge 2 may be quickly retracted when a small amount of force is applied against the edge of the gauge when it is in the operative position, as shown, for example, in Figure 3, the cammed 25 end 3 bears against a coil spring 13 which is inserted in a container 14 set into the head of the club. The cam 3 is so shaped that when a slight force is exerted against the gauge, the gauge will snap into the retracted position. A 30 washer 15 is interposed between the cam 4 and the spring 13.

In order to attach the gauge 2 to the club 7, the bottom of the club is hollowed out to receive the container 14 and members 8 which are secured to the bottom of the club by means of the screws 11. When the device is installed in the bottom of the club, the bottom of the members 8 and the gauge 2 lie flush with and form a part of the sole plate 16 of the club. One corner 17 40 of the gauge 2 is shaped so that one's fingernails may be readily inserted to raise the gauge 2 to operative position.

In Figure 3, I have shown a right-handed club with the member 2 in operative position substantially at right angles to the sole of the club at the beginning of the stroke. The golf ball 18 is shown resting on the tee 19.

Of course, the sole plate 16 of the club may 50 be so formed that both portions of it shown in Figure 1 and the members 8 may form an integral member, in which case it will be necessary to provide an opening in which the member 2 fits snugly and brackets would be provided 55

on the under part of the sole which would be hinged to member 2 by means of a pin.

The manner in which this golf club is used is obvious. At the beginning of the stroke, the member 2 is placed in the operative or extended position shown in Figure 3. If the swing is made properly, the gauge will just clear the ground and will have absolutely no effect on the swing. If, however, the forward swing is such that the sole of the club is closer to the ground than it was at the beginning of the stroke, the contact of the ground and the gauge will cause the gauge to be retracted promptly, aided by the operation of spring 13. The effect upon the golf stroke will be negligible. In case it is desired not to use the gauge, it will be left in the retracted position shown in full lines in Figure 2, in which case, the bottom of the golf club presents a continuous face or sole plate.

20 While I have herein illustrated and described a preferred embodiment of my invention, it will be understood that changes in the construction and relationship of the various parts may be made without departing either from the spirit 25 of the invention or the scope of my claims.

I claim:

1. A golf club having a head and a hinged member secured to the bottom of the head, which member may be set in an operative position 30 approximately at right angles to the bottom of the club and which when retracted by movement of the club, will lie flush with the sole of the club and substantially at right angles to its operative position.
- 35 2. A golf club having a head and a hinged member secured to the bottom of the head, which member may be set in a position approximately at right angles to the bottom of the club and which when retracted will lie substantially at right angles to the former position and flush with the sole of the club, said hinged member consisting of a plate having one end thereof shaped like a cam, and means for yieldably exerting pressure against said cam-like end.
- 40 3. A golf club having a head, a hinged member secured to the bottom of the head, which member may be set in a position approximately at right angles to the bottom of the club and which when retracted will lie flush with the sole 45 of the club, said hinged member consisting of a plate having one end thereof shaped like a cam, and a spring within the head cooperating with the cam of the plate for releasably holding the member in either position.
- 50 4. A golf club having a head and a hinged member secured to the bottom of the head, which member may be set in an operative position approximately at right angles to the bottom of the club, said member being retractible by 55 the contact of the member with the ground on the downward swing of the club, and which when retracted will lie substantially at right angles to its operative position and flush with the sole of the club, and a spring cooperating with said member whereby the member is assisted to a retracted position.
- 60 5. An attachment for a golf club consisting of a retractible member which when in operative position projects substantially normal to the sole 65 of the club and which when retracted lies in a position approximately at right angles to the operative position and flush with the sole of the club, means pivotally mounting said member on the sole of a golf club, whereby the club may 70 be spaced a predetermined distance from the

ground, and a spring cooperating with said member whereby the member is assisted to the retracted position.

6. An attachment for a golf club consisting of a retractible member which when in operative position projects substantially normal to the sole of the club and which when retracted lies in a position approximately at right angles to the operative position and substantially flush with the sole of the club, means pivotally mounting said member on the sole of a golf club, whereby the club may be spaced a predetermined distance from the ground, and a spring cooperating with said member whereby the member is assisted to the retracted position, said spring being enclosed 15 within the head of the club.

7. A golf club having a head with a ball engaging face, and gauge means connected to the head and movable from a projecting position where it extends below the bottom of the head to a retracted position where it is substantially flush with the bottom of the head and arranged to be moved to the retracted position when it contacts with the ground on the forward stroke of the club but cannot retract by contact with the ground on the back stroke of the club.

8. A golf club having a head, means pivoted adjacent the bottom of the head for spacing the head from the ground at the beginning of the playing stroke, said means being movable from the spacing position to a position approximately at right angles thereto by the contact of the spacing means with the ground during the down swing of the club.

9. A golf club having a head, a gauge element pivotally mounted on the head and projecting downwardly from the bottom of the head for spacing the club from the ground at the beginning of the playing stroke, said means being movable from the spacing position to a position 40 substantially at right angles therewith where it is substantially parallel to and flush with the sole of the club by the contact of the gauge element with the ground during the down swing of the club.

10. A golf club having a head, a gauge element carried on the head movable from an operative position where it projects substantially vertically downwardly beyond the bottom of the head to a position substantially at right 50 angles to the operating position of said gauge element where it is substantially flush with the bottom of the head, and means for resiliently holding said gauge in either position.

11. A golf club having a head, a recess in the bottom surface of the head, and a movable gauge element secured to the head adjacent the recess and movable from an extended vertical position where it projects below the bottom of the head to a retracted horizontal position where it is substantially received in said recess.

12. A golf club having a head, a recess in the bottom surface of the head, a movable gauge element secured to the head adjacent the recess and movable from an extended position where it projects downwardly below the bottom of the head to a retracted position substantially at right angles to the extended position where it is received in said recess, and means for releasably holding the gauge element in either 70 position.

13. A golf club having a head, and a spacing member secured in a recess in the bottom surface of the club head for elevating the sole of the club a predetermined distance from the 75

ground, said member being movable from the spacing position which is normal to the sole of the club to a position in said recess by contact of said spacing member with the ground during the down swing of the club.

5 14. A golf club having a head, a hinged member secured to the bottom surface of the head,

which member may be set in an operative position approximately at right angles to the bottom of the club and which, when retracted by movement of the club, will assume a position which is not less than a right angle from its original position.

WILLIAM H. MCKENNA.
